UNITED STATES PATENT OFFICE.

WILLIAM CLIFFORD, OF DULUTH, MINNESOTA.

DREDGE-ANCHOR.

No. 800,267.

Specification of Letters Patent.

Patented Sept. 26, 1905.

Application filed March 27, 1906. Serial No. 252,115.

To all whom it may concern:

Be it known that I, WILLIAM CLIFFORD, a citizen of the United States, residing at Duluth, in the county of St. Louis and State of Minnesota, have invented certain new and useful Improvements in Dredge-Anchors; and I do hereby declare the following to be a full, clear, and exact description of the invention, such as will enable others skilled in the art to 10 which it appertains to make and use the same.

My invention relates to dredge-anchors, and has for its object the provision of an anchor having a foot which will form a broad support for the anchor post or spud, and which 15 will take firm hold of the submarine ground, and which may be lifted without excessive resistance from the water or suction by mud.

It consists, in combination with an anchor post or spud, of a transversely-extending plate 20 or flanged collar, bolted to said post at or near the lower end thereof, and two wing-plates pivotally bolted to said post at or near its said lower end and adapted to open upwardly against the upper said plate.

25 It also consists of such other constructions, combinations, and arrangements of parts, as will be hereinafter described and claimed.

In the accompanying drawings, Figure 1 is a perspective view of a portion of a dredge-30 anchor post, showing my invention. Fig. 2 is a plan view of said invention, showing the anchor-post in horizontal section. Fig. 3 is a central vertical section of my said invention across the axis of said bolt, and Fig. 4 is 35 a central vertical section along the axis of said bolt.

In the drawings, 1 is an anchor-post such as is commonly used to anchor dredges, to which I secure by any suitable means, as by the bolt 40 2, a plate 3, preferably ribbed, as at 3^a. Beneath said upper plate I hinge to said post in any suitable manner and by any suitable means, preferably by said bolt 2, extending therethrough, a pair of folding or wing members 45 of any suitable construction, as 4 and 5, which are adapted to swing upwardly on their hinge and facially contact with the upper said plate when said anchor rests upon or in the submarine ground. These wings are adapted 50 to form a substantial resistance to the upward pressure of the mud and are of greater area than said upper plate and by reason of their contact with the said upper plate are limited as to their upward swing. It is thus obvious

that great downward pressure may be exerted 55 upon said post or upper plate without forcing said foot any great distance, if at all, into the solid earth or sand. The central passage for said post through said upper plate or collar is preferably large enough in one diameter 60 to allow for a little play, so that the plate may tip a little by pivotal action on said bolt. The post-passage through the hinged lower plates is made sufficiently large to enable said lower plates to swing a short distance downwardly on said hinge before their inner edges contact with said post. When it is desired to raise said anchor, lifting power is applied to the post in the usual manner well known to the art and not thought necessary to be more 70 particularly described herein. Such operation has heretofore been attended with considerable difficulty in starting the anchor on account of the great suction established beneath the anchor-foot by the mud. In my 75 device above referred to this excessive suction is avoided by the downward swing of the said wings as the lifting strain is put upon the anchor, which wings are thus drawn from the earth at an angle instead of flatly upward. 80 I do not, however, desire to be restricted to foot members of the specific contours or designs illustrated nor to the specific style of hinge shown for securing said foot on the several members thereof in position, as these 85 features are obviously capable of some alteration or modification within the spirit and scope of my said invention.

Having now described my invention, what I claim, and desire to secure by Letters Patent, is—

1. In a dredge-anchor, the combination with an anchor-post, of a foot comprising a plate or flanged collar secured to said post at or near the lower end thereof and adapted to 95 rock thereon, wing members hinged to said post and extending below said plate and adapted in operative position to swing upward into facial contact with said plate or flanged collar and in retracted position to swing away 100 from said plate or flanged collar at an angle thereto.

2. In a dredge-anchor, the combination with an anchor-post, of a ribbed flange member secured to said post at or near the lower end 105 thereof, ribbed members hinged to said post and extending below said flange member and adapted in operative position to swing upward

into facial contact with said flange member, substantially as described.

3. The combination with a post of a flange member pivotally secured thereto, wing members pivotally secured to said flange member and extending below the same and adapted in operative position to swing upward against said flange member and in retracted position

to swing downward at an angle to said flange member.

In testimony whereof I hereunto affix my signature in presence of two witnesses.

WILLIAM CLIFFORD.
